UNITED STATES PATENT OFFICE

2,418,776

METHOD AND APPARATUS FOR CENTRIFUGALLY WASHING SUGAR, CHEMICALS, ETC.

Frederick W. Kopplin, Hardin, Mont.

Application May 25, 1942, Serial No. 444,416

3 Claims. (Cl. 210—67)

1

This invention relates to improvements in methods and apparatus for the centrifugal washing of sugar, chemicals or other materials.

The primary object of this invention is the provision of an improved method and apparatus for the intermittent washing of materials, such as sugar, during the normal washing period.

In the centrifugal purification of sugar or other like materials, the cycle of operation generally includes a first step of centrifugal elimination of free syrup from the sugar grains, and then the centrifugal washing of the resultant sugar grains in order to remove the coating of syrup that adheres thereto; this washing being accomplished by means of a spray directed against the revolving sugar mass. The present invention is principally concerned with the washing step. In conventional centrifugal machines, a wash control head is provided for the automatic starting and stopping of the washing fluid. During the washing period the conventional machine continuously sprays the sugar. However, I have found that by intermittently controlling the off and on operation of the spray during this washing period, a more efficient dissipation of the impurities is accomplished, with an increased yield in the pure product; thus doing away with the necessity of reprocessing large percentages of the material being treated.

Other objects and advantages of this invention will be apparent during the course of the following detailed description.

In the accompanying drawings, forming a part of this specification, and wherein similar reference characters designate corresponding parts throughout the several views,

Figure 1 is a diagrammatic representation of conventional sugar treating centrifugal machinery and its automatic cycle controls, with my improved mechanism associated therewith for the intermittent washing of the sugar during the washing period.

Figure 2 is a view of a circuit regulating cam associated with my intermittent control.

Figure 3 is a side elevation, partly in section, of my improved mechanism for variably controlling the intermittent washing of sugar, chemicals, etc., in a centrifugal.

Figures 4, 5, 6 and 7 are details of the cam mechanism for varying the washing period between the intermittent off periods, as controlled by the improved mechanism of Figure 3.

Figure 8 is a fragmentary view, partly in section, showing the manner in which the cam arrangement is manipulated.

2

Figure 9 is a diagrammatic representation of the intermittent washing control shown in Figure 1, but with the switch contacts in a different relation in the controlling circuit.

5 In the drawings, wherein for the purpose of illustration is shown the preferred embodiment of the invention, the letter A may generally designate centrifugal machinery for the washing of sugar, chemicals and the like, having a spray mechanism B associated therewith which is automatically controlled as to the washing period by mechanism and means C. Associated in a cooperative relation with the mechanism C is my improved mechanism D for the intermittent control of the spray during the washing period.

The centrifugal mechanism A may be of the type generally shown in such United States patents as 1,627,868; 1,826,675 and 2,128,575, and of the type manufactured by the Western States 20 Machine Company of Hamilton, Ohio. Such mechanism generally includes centrifugal apparatus A having a rotary centrifugal basket 10; basket suspension shaft 11 and casing 12, the operation of which will be well understood by 25 those skilled in the art to which this invention relates.

The spray mechanism B is adapted to produce a plurality of fine sprays for washing the material in the centrifugal. The washing medium is 30 controlled by valve 20 ordinarily controlled by the automatic wash control head mechanism C above referred to.

The centrifugal equipment is generally of that type manufactured by the Western States Machine Company, such as shown in part in prior U. S. Patents 1,627,868; 1,826,675 and 2,128,575. With this centrifugal mechanism is associated automatic control mechanism also manufactured by the Western States Machine Company for 40 controlling the cycles of the different steps automatically, and shown at least in part in such prior U. S. patents as: 1,719,132; 1,758,901 and 1,861,978.

Conventional automatic wash head equipment includes a shaft 30 driven by suitable motor and 45 gear reducing mechanism (not shown). A longitudinally movable rod or member 31 is associated therewith for normally controlling the operation of the spray valve. In the case of the present invention, however, this part 31 operates a switch 32 which controls a circuit thru a solenoid 33. The latter is associated with the valve 20 and opens the valve upon energization 50 of this circuit.

The mechanism for intermittent control of the 55 materials in the centrifugal during the washing

period comprises a switch mechanism 50 operated by variably adjustable timing cam means 51. The latter is mounted upon a suitable shaft 52. This shaft 52 is driven by means of a motor 53 thru a gear reduction mechanism 54 of conventional type. A rheostat 55 may be associated with the motor for varying the speed thereof.

The cam mechanism 51 is of a type which can be manually adjusted so as to vary the off and on period of the switch mechanism 50.

The switch mechanism 50 preferably includes two pairs of contacts for the same circuit; only one pair of contacts being disposed in the circuit at any one time, for purposes to be subsequently mentioned. One pair of these contacts 55^a and 56 has associated therewith a switch arm 57. The other pair of contacts 58 and 59 has another arm 60 associated therewith. Thus it can be seen that the mechanism includes two pairs of contacts. The power circuit is connected to only a single pair of the contacts at any one time, depending on the desired operation of the device. It is adapted to be disconnected therefrom and connected to the other pair of contacts for different desired operation of the device, as will be hereinafter described. These switch arms 57 and 60 are connected together and pivoted at 61. The housing 62 of the switch mechanism 50 is provided with a reciprocating spring controlled rod 63 having a bifurcated portion 65 thereon loosely receiving an extension of the connected switch arms, so that depending upon the position of the rod 63, the switch arm 57 will be engaging the contacts 55^a and 56 or the arm 60 engaging the contacts 58 and 59. Normally the spring urges the rod 63 in position so that the switch arm 57 is out of engagement with the contacts 55^a and 56.

The circuit 80 receives current from any approved source and in this circuit 80 is disposed a switch 32 and a solenoid 33 which it controls. Normally, the spring 32 of the switch 32 holds the circuit 80 open directly on the opposite side of the solenoid 33 from the valve 20, so that it is necessary for the automatic wash head C to close the switch through the part 31. The switch 32 is, of course, also located in the circuit 80 and connected therewith either by the pair of contacts 55^a and 56, or the pair of contacts 58 and 59.

Cam means 51 for regulating the off and on period of the switch 50 comprises a pair of cam discs 53 and 51. The cam disc 53 is keyed at 66 upon the shaft 52. It is provided with a throw portion 54 thereon extending a distance less than 180° around the cam.

The cam disc 51 is provided with teeth 66 centrally thereof adapted for slidable or splined connection upon the teeth 57 formed integral with the cam disc 53. This cam disc 51 is also provided with a throw portion 58 extending for a distance of less than 180° circumferentially thereof.

The throw portions of the cam discs 53 and 51 are complementary and adapted to operate a pivoted control arm or member 100. The latter is pivoted at 101 upon the casing of the switch 50 and at its free end engages an end of the rod 63. Intermediate its ends this pivoted arm 100 is provided with a roller 110 normally urged by the spring of the rod 51 against the peripheral or circumferential surfaces of the cams 53 and 51.

The cam disc 51 is provided with an integral sleeve portion 110 thereon wherein is disposed a spring 116 under compression. This spring normally engages a detachable disc 117 and forces

the disc cam 51 towards the disc cam 50. The opposite end of the spring 116 engages the washer or disc 120 detachably connected at 121 upon the outer end of the shaft 52, as shown in Figures 3 and 8 of the drawings.

It is readily obvious that the throw arc of the cam arrangement 51 can be varied by pulling the cam disc 51 away from the cam disc 50 and rotating it to the position desired. It is noted from Figures 1, 2 and 4 of the drawings that the throw surface of the cam disc 50 is graduated and of course the shoulder 125 at the end of the throw of the cam disc 51 may be associated with these delineations to determine the throw arc of the cam which is effective for closing the switch 50.

With the contacts 55^a and 56 disposed in the circuit 80, a period of switch closing of the circuit through this switch 50 cannot be made shorter than the period of broken contact or opening of the circuit. That is true because throws of both of the cam discs 50 and 51 extend through substantially 180°. However, the closing of the circuit 80 through this switch 50 can be made shorter than the period of broken contact by transposing the ends of the wires of the circuit 80 out of connection with the contacts 55^a and 56 and into connection with the contacts 58 and 59. Under these circumstances, the switch 50 will close the circuit 80 when the roller 110 is in the depression of the cam mechanism 51; that is, off of the throw portions.

Referring to the operation, the master control or automatic wash control head C commences to function upon starting the centrifugal washing operation and during the entire period of the washing step of treatment of the sugar or other materials being washed, this wash head will hold the member 31 down and close the circuit 80 through the switch 32. Of course the circuit 80 when closed holds the valve 20 open through operation of the solenoid 33. However, during this wash period, the washing spray is intermittently controlled as to its effective "off and on," by means of the intermittent circuit maker and breaker mechanism D which operates as above described to intermittently make and break the circuit 80 during the wash period as automatically regulated by the automatic wash head C. Of course any time the switch 50 closes the circuit 80, the solenoid 33 is operated to open the valve 20.

The time period of washing as controlled by the means C is determined, as is also the time of each of the washing periods controlled by the intermittent operating device D, by the nature and degree of impurity of the material being treated. It will be obvious that those skilled in the art can readily determine these time factors.

As shown in the drawings, any number of the centrifugals in a battery or set-up of centrifugal machines may be employed.

Changes in details may be made to the form of invention herein shown and described, without departing from the spirit of the invention or the scope of the following claims.

I claim:

1. The improvement in the method of centrifugal purification of sugar and like solids wherein there is a purging treatment followed by a centrifugal washing step of predetermined length, which consists in the intermittent washing of the sugar or like solids being centrifugally treated for the entire washing step.

2. In centrifugal apparatus for treating sugar and other materials for the removal of certain

centrifugally separable impurities and parts therefrom, the combination of a centrifuge, a valve for admitting a washing medium to the centrifuge, a solenoid for operating said valve, a switch in circuit with the solenoid, an automatic control mechanism for controlling the opening and closing of said switch for a predetermined period of time, and control means comprising a second switch in series in the circuit with said first switch, and means for intermittently opening and closing said last mentioned switch during the aforesaid predetermined time.

3. In apparatus for the centrifugal purification of sugar or other centrifugally separable materials, the combination of a centrifuge wherein the materials are to be washed; means for supplying washing fluid to the materials in the centrifuge including a valve, an electric circuit, control means in said circuit for operating said valve including a switch in the circuit and a control device for opening and closing said switch and

5 the circuit in which it is placed, a second switch in said circuit, and a second control means for the second switch including means for intermittently opening and closing said second switch.

10 FREDERICK W. KOPPLIN.
